UNITED STATES PATENT OFFICE.

FREDERICK E. FAY, OF BRYAN, OHIO.

WHEELBARROW.

SPECIFICATION forming part of Letters Patent No. 390,356, dated October 2, 1888.

Application filed January 27, 1888. Serial No. 262,161. (No model.)

To all whom it may concern:

Be it known that I, FREDERICK E. FAY, a citizen of the United States, residing at Bryan, in the county of Williams and State of Ohio, have invented certain new and useful Improvements in Wheelbarrows; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

My invention relates to wheelbarrows, and has for its object to provide the barrow with a device to be attached to the side thereof at the front and rear to hold the removable sides in place and to permit of the easy insertion and removal of the sides, and it is particularly adapted for use on what are known as "box" or "tray" barrows.

The device is of a construction that forms a loop or groove in which the ends of the removable sides will fit, so that while the sides may be dropped into and lifted out of the slot or groove the outside or outer wall of the slot or groove will hold the removable side in place. The construction may be of different forms for effecting the same result, and several of the forms will hereinafter be described; but it is not intended to limit the invention to any particular form. The invention will, however, be hereinafter particularly described and claimed, reference being had to the accompanying drawings, forming a part hereof.

Figure 1 is a perspective of barrow with one side-board removed. Fig. 2 is a perspective of front end of barrow, on an enlarged scale; Fig. 3, a similar view showing a modified form of iron; Fig. 4, a similar view showing another form; Fig. 5, a perspective of front end of barrow with a modified form of iron. Fig. 6 is a perspective of front end of barrow with one form of iron that may be used; Fig. 7, a rear end with another form of iron; Fig. 8, a front end view with another form and showing the side-board in place.

In the drawings there is shown a barrow with its body A made in hopper shape of the form shown, being composed of the removable side-boards B and the end-boards B', said end-boards inclining inwardly from the top down-

wardly to form the hopper-shaped body. These side-boards B may be flaring, but are preferably perpendicular, and are held in place on the barrow by irons C, each iron constituting a slot, groove, or way, and may be a loop in which the sides will fit. The preferred form is that shown in Figs. 1 and 2, in which the iron is composed of two upright rods or bars, D and E, one of them—say E—set forward of the other, as shown. These bars are connected together at their ends by necks F, the rods or bars where the necks join them being formed, respectively, with extensions or lugs G and H. These necks form at each end of the bars or rods a depression, groove, recess, or way adapted to receive a part of the end of the removable sides B. The bar or rod E, which sets forward of the other, will bear against the face of the removable side-board when the latter is in place, and thus hold the side-board in place. The groove, recess, or way permits the side-board to be dropped into place and lifted when to be removed, and thus a box or tray barrow is formed with removable sides.

The irons C may be of any suitable form in cross-section; but it is preferred to make the bar or rod D flattened or oval on one side and flat on the other, so that it may fit close against the face of the front or rear end-board when in place, and so also may the rod or bar E be flattened on one face—say on the face which bears against the outer face of the removable side-board, as shown in Fig. 3. They may be secured in place by any suitable means—for instance, by screws passed through the rods or bars D into the end of the barrow, or otherwise.

The iron may be cast in one piece, as shown in Fig. 3, or it may be of metal bent into form, as shown in the other figures. When the iron is made in either of the forms described, it is applied, preferably, so as to bring the upper edge below the top edge of the end of the barrow, as shown in Figs. 1 and 2, the bar D then lying against the outer face of the end-board with the bar E extending along the edge of the end-board, but away from contact therewith, so as to permit the side board to fit in place. The bar or rod D, however, may be omitted, partially as shown in Fig. 4; but even in that event the grooves, ways, or recesses would

still be retained, as shown; but the iron is stronger when the rod D is made continuous. If desired, the rod D may be omitted altogether; and in that case the extension or lug 5 G might be extended laterally or otherwise, as shown in Fig. 5, so that it may lie against the face of the end-board for the passage of a screw or other fastening to hold it in place. So, too, the extension or lug G may be omitted 10 and the neck extended, so as to lie against the end-board; in which event—as, for illustration, in Fig. 7—the neck may lie on the top edge of the end-board; but even in such form the depression, groove, or way is retained, the lug 15 or extension H and the neck together forming the same.

If desired, the recess or groove may be omitted from one end of the iron, as shown in Fig. 7; but in such case I would arrange the irons 20 on the barrow, so that at one end-board the grooved or recessed portion of the iron would be at the top of the board and at the other end-board it would be at the bottom, the end of the iron not having the groove or recess being 25 extended laterally, so as to lie upon the secured thereto.

tion is to omit the bars D
thus forming a hook, as
t even in that case the
ained, so that the side-
d into and lifted out of it.
forming the groove or
d at only one end of the
of the barrow being pro-
med by the iron C', hav-
g ht angles and secured,

4 instead of using screws or
gs to secure the irons in
ured by turning or bend-
ng it into or else through
 clinching its ends, as
art of Fig. 8.

constructions described
way the irons will allow
slipped down into place,
cess, and will securely
out in place, and thus I
net a combined side and
s the sides of the box or
novable. Furthermore,
at the laterally-extended
not only attached to the
ions of the barrow, but
ereto, and that such lat-
ired ends hold the irons
ls so that the side-boards

6 simple in construction, m inexpensive to manu-
sily applied, and besides d supports for the side
> to protect or shield and f the barrow. It is ob-
he irons could be cast so

that the two rods or bars D and E would be connected together throughout their length by a web; but such construction while having the groove would only increase the quantity of metal and add to the cost of manufacture. So, too, it is apparent that changes in the details of construction can be made without departing from the spirit of my invention.

The bottom I, instead of being smaller at the front than at the rear, as usual in this class of barrows, is made as wide practically at the front as at the rear, thus throwing more of the weight onto the wheel. 75

It will be understood that by the expression "iron" I do not mean that the device is necessarily made of iron, as it may be of any suitable material, the expression being merely a designating phrase, whether the device be of metal or other material. 85

Having described my invention and set forth its merits, what I claim is—

1. An iron for securing a side-board to a barrow, formed with a groove, recess, or way open across its top to receive and permit the end of the side-board to drop therein and be lifted therefrom, substantially as described.

2. The iron for securing the side-board to a barrow, composed of the two bars or rods connected together by a neck, forming a groove or way to receive the end of the side-board, substantially as described.

3. The iron for securing the side-board to a barrow, composed of the rods or bars provided with extensions or lugs connected together by a neck to form a groove, recess, or way to receive the end of the side-board, substantially as described. 100

4. The iron for securing the side-boards to a barrow, composed of the two rods or bars connected together by a neck to form a groove or way, one of said rods or bars being set forward of the other, substantially as described. 105

5. The combination, with the end-boards of a barrow, of irons having their ends extended laterally, and rigidly secured to the upper and lower parts of the barrow at the front and rear ends thereof, to hold said irons out from the ends to form spaces for the reception of the ends of the side-boards, at least one set of which irons shall be formed into a groove or recess open across its top to permit the vertical movement of the side-boards therein, substantially as described. 110 115

6. The combination, with the front and rear end-boards inclined inwardly from the top to the bottom, of the removable sides, to form, in connection with the end-boards, a hopper-shaped body, and irons secured to the front and rear ends of the barrow and set out from the ends to receive the ends of the side-boards, at least one set of which irons shall be formed into a groove or recess open across its top to permit the vertical movement of the side-boards therein, substantially as described. 130 125 130

7. A wheelbarrow having a hopper-shaped box or tray formed with inclined front and

rear ends and provided with side-boards removable independent of the front and rear end-boards, substantially as described.

8. A wheelbarrow provided with a groove or recess at the sides of its end-board open across its top adapted to receive the end of the side-board and permit the same to be moved vertically therein, substantially as de-

scribed, for the insertion and removal of the side-board, for the purposes set forth. 10

In testimony whereof I affix my signature in presence of two witnesses.

FREDERICK E. FAY.
